Patented Dec. 4, 1973

229,463

CABINET AND SERVICE UNIT FOR DENTAL CLINICS, DENTAL OFFICES AND THE LIKE PROVIDING A PLURALITY OF CUBICLES

Kenneth C. Marshall, Clayton, Mo., Peter G. Sotiropoulos, Belleville, Ill., and Anton M. Piros, St. Louis County, Mo., assignors to The Orthodontic Education and Research Foundation, St. Louis, Mo.

Filed Aug. 2, 1971, Ser. No. 168,511

Term of patent 14 years

Int. Cl. D6—04

U.S. Cl. D6—162

FIG. 1

FIG.2

FIG. 3

FIG. 4

FIG. 1 is a perspective of our new cabinet and service unit for dental clinics, dental offices and the like providing a plurality of cubicles;

FIG. 2 is a plan of FIG. 1;

FIG. 3 is an elevation as viewed from the side on line 3—3 of FIG. 2 or any of the other three sides of FIG. 2;

FIG. 4 is an elevation on either of lines 4—4 of FIG. 2.

The bottom of the unit rests on the floor and is plain and unadorned.

We claim:

The ornamental design for a cabinet and service unit for dental clinics, dental offices and the like providing a plurality of cubicles, substantially as shown and described.
